UNITED STATES PATENT OFFICE.

DAVID ROUSSEAU, OF NEW YORK, N. Y.

ELECTRIC GAS-LIGHTING BURNER.

SPECIFICATION forming part of Letters Patent No. 328,977, dated October 27, 1885.

Application filed May 13, 1884. Serial No. 131,366. (No model.)

To all whom it may concern:

Be it known that I, DAVID ROUSSEAU, of Mott Haven, in New York city, State of New York, have invented certain new and useful 5 Improvements in Electric Gas-Lighting Burners, of which the following is a specification.

My invention applies to that class of burners in which the movement of a lever pivoted on the burners operates the gas-valve to turn 10 on the gas and simultaneously actuates the electrodes to produce the igniting-spark.

In most all burners of this type the valve used is a rotary friction-plug of the common form, and is revolved by a ratchet movement 15 of the lever. In a former application filed by me October 6, 1883, No. 109,071, I show a burner provided with a minute double-seating puppet-valve, which works without packing or friction in a direction across the gas-passage of the burner, and it is operated by a valve-lever which is actuated by cam-pins on a ratchet-wheel, which latter is revolved by the pawl-lever or sparking-lever, and so arranged that each alternate forward step of the lever and 25 ratchet will open the valve and ignite the gas, while each intermediate forward step will close the valve and extinguish the gas, the backward movement of the pawl-lever being always idle.

Now, in my present device I dispense entirely with the ratchet and cam wheel between the valve-lever or sparking-lever, and I form a direct engagement between the valve-lever and the sparking-lever, so that the forward 35 movement of the lever opens the valve and produces the igniting-spark, whereas the back movement of the lever positively closes the valve. I also pivot a large pawl or pawl-lever on the sparking-lever and limit its movement on the sparking-lever by a stop, and connect the pendent manipulating pull to one arm of this pawl-lever, while the other arm of the pawl-lever is arranged to engage a locking projection on the burner in the arc of motion of the lever, and to this end of the pawl is attached a second pull-cord. When, therefore, the first cord is pulled, the pawl and sparking-levers move around together, and thus open the valve and separate the sparking-points until, finally, the tip of the pawl 45 rides over the projection, and thus locks the

parts in the open position. When, however, the second cord is pulled, the pawl is released, and both pawl and electrode lever are caused to fly back by the action of a spring, so as to 55 close the valve and extinguish the gas. One of the said cords passes through a perforated knob or loop sliding on the other cord, so that both cords can be held in the same hand and either operated easily to close or open the 60 valve without causing either cord to fly out of place when the lever is allowed to spring back to close the valve.

My present invention therefore consists, mainly, in the features above outlined, as hereinafter fully set forth.

In the drawings annexed, Figure 1 represents a front elevation of my improved burner with the valve closed and the parts in their positions of repose. Fig. 2 is a similar view 70 with the pawl and sparking-lever pulled over into their locked position with the valve opened. Fig. 3 is a side elevation of the burner with the parts in the position of Fig. 1, and viewed from the right or valve side of 75 the burner. Fig. 4 is a rear elevation of the burner with the parts in the position of Fig. 1, and shown partly in section to illustrate the action of the valve, &c.

Referring to the figures, *a* indicates the body 80 of the burner, which is preferably cast in brass, as usual, having a gas-passage extending through it, with a screw-socket at the base to screw onto the fixture, and a ground socket at the top to receive the lava 85 or other jet tip, as usual. The gas-passage *b* does not extend straight through the burner, but is somewhat eccentric and zigzag, as shown well in Fig. 4, substantially the same as in my former burner, and at the bend or 90 zigzag part of the passage is formed a small recess or valve-chamber, *c*, in which a small double-faced puppet-valve, *d*, works, as shown best in Fig. 4. The stem *d'* of this valve projects freely through a small screw-plug, *e*, 95 which is screwed into a threaded bore in the side of the burner coincident with the valve-chamber *c*. On the base of the valve-chamber *c* is formed a conical-ground seat to meet with one face of the valve while the inner end 100 of the plug *e* is formed with a similar seat to meet with the other face of the valve. The

extremity of the valve-stem d' projects, of course, from the head of the plug e , for operation as shown, and it will now be readily seen that when the valve is forced inward it 5 will seat on the seat of the valve-chamber, as shown in Fig. 4, and hence shut off the flow of gas to the tip, whereas when the valve is moved outward it will seat on the seat of the plug e , and prevent the escape or leakage of 10 gas around the unpacked stem d' , while allowing the gas to flow freely to the jet-tip; hence this form and arrangement of valve, while being very simple, works without packing, and hence practically without friction, so 15 that it is therefore operated with ease and certainty, and is hence admirably adapted for burners of that class, as already set forth in my former application.

Now, referring to Figs. 1 and 2, f indicates 20 the main operating-lever of the burner, which may also be termed the "sparking" or "electrode" lever, as the long arm f' of the lever forms the movable electrode, which makes and breaks contact with the yielding electrode g , to 25 produce the igniting-spark in the well-known manner of burners of this class, which is sufficiently illustrated in the drawings, and needs no description here other than to state that the special arrangement of electrodes here 30 shown is the same as that patented to me in Patent No. 235,024, of November 30, 1880. The electrode-lever f is an elbow-lever pivoted at the hub or bend on a stud or screw, h , which screws into a boss, i , on the side of the burner, 35 as shown best in Figs. 1 and 3. In the lower edge of the hub of the lever is cut a wide notch, j , which is coincident with a tooth or projection, k , which projects from the burner, and the ends of this notch will strike against 40 either side of the projection k when the lever is moved in either direction, and thus form stops to limit said motions.

Around the boss i , behind the lever f , is coiled a spiral spring, l , one end of which engages with the projection k , while the other end engages the arm f' of the lever f , as shown best in Figs. 1, 2, and 3, so as to exert a constant tension to swing the lever in the position shown in Figs. 1, 3, and 4, with 45 one end of the notch j against the tooth k . The lever f is also formed with a short arm, f'' , at about right angles to the arm f' , and on the end of this short arm is pivoted a large pawl or pawl-lever, m , one arm of which projects 50 outward in line with the arm f'' , while the other arm is curved around the hub of the main lever f , and is terminated with a pawl-tip, m' , which normally lies against the projection k . The pawl-lever has only a limited 55 play on the lever f' and to and from the projection k sufficient to engage and disengage with the projection by reason of a stop-pin, n , on the lever, which strikes against a shoulder, n' , on the arm f'' .

60 The gas-valve d is operatively connected with the aforesaid levers by means of the

forked valve-lever $o p$, which is pivoted on the pin p' between ears o' , at the base of the burner, and one or both of the arms $o p$ of the valve-lever are springy or yielding. The arm o of the valve-lever is cleft at the tip and engages the grooved head or tip of the valve-stem, as well shown in Figs. 3 and 4, while the other arm, p , is bent or curved to one side toward the hub of the main lever f , and the tip of this arm is bent outward and engages with an eccentric slot, r , cut in the hub of the lever f , as well shown in Figs. 1, 2, and 3. It will hence be observed that when the levers lie in their position of repose, as in Figs. 1, 2, 75 and 4, the tip of the valve-lever will be at the inner end of the eccentric slot and the valve will be closed, (see Figs. 1 and 4); but if the lever f be swung around, as in Fig. 2, the tip of the valve-lever p will traverse the slot r toward the outer end thereof, and the valve will be opened, as indicated in Fig. 2; whereas, if the lever f be again released it will fly back into the position of repose and positively close the valve, as seen in Figs. 1 and 2. The throw 80 of the slot r and the tension of the spring-arms $o p$ of the valve-lever are such that a movement is imparted to the lever a little greater than the throw of the valve, so that the overplus of motion slightly flexes the spring-arms, 85 and thus keeps a constant elastic pressure on the valve, to hold it snugly to its seat when moved either in or out, as will be readily comprehended.

Referring now to Figs. 1 and 2, it will be 90 seen that a pendent manipulating cord or chain, s , depends from the tip of the pawl-lever m and connects to a perforated loop or knob, s' , while a second cord or chain, t , depends from the upper arm of the pawl-lever, 95 passes through the loop s' , and connects to a manipulating knob or ball, t' .

The entire construction being now delineated, the operation will be readily understood. When, therefore, the burner is in a condition 100 of repose with the gas turned off, the parts will be in the positions shown in Figs. 1, 3, and 4. If it is now desired to turn on and light the gas, it will only be necessary to seize the knob t' and pull down the cord t . This will 105 exert a downward strain on the pawl-lever m , which will press its pawl-nose against the projection k , and move both the pawl-lever and the electrode-lever f around in a curve, as indicated by the arrow in Fig. 2, which movement will open the valve in the manner before described and turn on the gas, and at the same time cause the arm f to first engage the electrode g , as shown by dotted lines in Fig. 2, and then break contact therewith, as shown 115 by full lines, and thus produce an igniting-spark to light the issuing gas, while, finally, the catching-shoulder of the pawl will ride over the projection k and fall into engagement 120 therewith, as shown by full lines in Fig. 2, thus holding the parts locked in said position 125 with the valve open and the gas lighted, as 130

will be readily understood. When it is desired to extinguish the gas, it is only necessary to seize the knob *s*' and pull down the cord *s*, which will slip the pawl *m*' from the projection *k*, and thus allow the levers to fly back into their positions of repose by the action of the spring *l*, as shown in Fig. 1, which will of course close the valve, as seen in Fig. 4, and extinguish the gas.

10 It will now be seen that by having the main cord *t* pass through a loop on the releasing-cord *s*, the main cord is prevented from flying up high out of place when the levers spring back, as it is restrained by passing through 15 the loop *s*' and through the fingers which seize the loop, for it will be seen that if the cord was left free it might be liable to be jerked up violently against the glass globes on the fixture and injure the same; but this is prevented 20 by the simple means described.

It will be also seen that the general mechanism of this burner is simple and positive, and that one forward motion of the levers opens the valve and lights the gas, and one 25 backward movement closes the valve and extinguishes the gas, and by reason of the special form of valve used and the direct operative connection between it and the sparking-lever these movements are rendered very easy 30 and the action of the burner very reliable.

It will be readily understood that in lieu of having the valve-lever engage with the sparking-lever by means of the cam-groove or eccentric groove *r*, any other operative connection 35 may be used.

I do not of course confine myself to the cords *t* *s* for operating the pawl-lever, as these cords may be entirely dispensed with and the pawl-lever *m* operated directly by the hand.

40 What I claim is—

1. The combination, with a gas-burner, of a reciprocating puppet-valve moving in a chamber in the body of the burner and controlling the gas-passage thereof, with a sparking-lever mounted on the burner, a manipulating device for operating said lever, and a direct positive operative connection between 45 said lever and said reciprocating valve, arranged and operating substantially as herein 50 set forth.

2. The combination, with a gas-burner, of

a reciprocating puppet-valve moving therein and controlling the gas-passage thereof, with the operating-lever *f*, pivoted on the burner, and provided with the cam-groove *r*, and with 55 a second lever connected with the stem of said valve and engaged with the said groove in the lever *f*, and with means, substantially as set forth, for moving said lever *f* back or forth and holding it in either of its positions, substantially as herein shown and described.

3. The combination, with a gas-burner, of a lever, *f*, pivoted on the burner, and a valve controlling the flow of gas through the burner, with a positive operative connection between 65 said valve and lever, with the pawl-lever *m* pivoted on the lever *f*, having one arm projecting outward and the opposite arm projecting inwardly and arranged to engage a stop or projection, *k*, with a manipulating-cord or 70 its equivalent extending from the respective arms of the said pawl-lever, substantially as herein shown and described.

4. The combination, with a gas-burner and a valve therein for controlling the flow of gas, 75 of a lever mounted on the burner and operatively connected with the valve, a spring tending constantly to move the lever back and close the valve, with a pawl-lever pivoted on the lever and adapted to engage a stop when 80 the lever is moved over to hold the valve open, with a manipulating-cord arranged to pull the said lever or levers over into the position to open the valve, and a second cord arranged to release the pawl and allow the levers to fly 85 back to close the valve, one of said cords passing through a loop on the other cord, substantially as and for the purpose set forth.

5. The combination, with a gas-burner with a valve to control the flow of gas, of the sparking-lever *f*, operatively connected with said 90 valve and having a retiring spring, *l*, with the pawl-lever *m*' pivoted to said sparking-lever and having a limited play thereon, and the locking projection *k*, with which said pawl 95 engages, arranged and operating substantially as and for the purpose set forth.

DANIEL ROUSSEAU.
